UNITED STATES PATENT OFFICE

92,350

DESIGN FOR A MEDALLION HOLDER

Herbert V. Henderson, Franklin Village, Mich.

Application December 21, 1933, Serial No. 50,174

Term of patent 7 years

To whom it may concern:

Be it known that I, HERBERT V. HENDERSON, a citizen of the United States, residing at 26705 Irving Road, in the city of Franklin Village, county of Oakland and State of Michigan, have invented a new, original, and ornamental Design for Medallion Holder, of which the following is a specification, reference being had to the accompanying drawings, forming part thereof, in which:

Fig. 1 is a front elevational view of a medallion holder showing my new design.

Fig. 2 is a top plan view.

Fig. 3 is a side elevational view of the same.

I claim:

The ornamental design for a medallion holder substantially as shown.

HERBERT V. HENDERSON.
